(57) **CLAIM**

The ornamental design for a fuel canister dispensing valve, as shown and described.

DESCRIPTION

FIG. 1 is a perspective view of a fuel canister dispensing valve showing our new design;

FIG. 2 is a front view of the valve shown in FIG. 1;

FIG. 3 is a rear view thereof;

FIG. 4 is a top view thereof;

FIG. 5 is a left side view, the right side being identical thereto; and,

FIG. 6 is a bottom view of the present valve.
